CLOTHESLINE HOLDER

Frank L. McConnell, Springfield, Ill.

Application July 27, 1935, Serial No. 33,518

3 Claims. (Cl. 24—133)

My invention relates to rope hangers in general and supports for one end of a rope extending from one place to another and relates particularly to clothesline hangers; an object being in my device 5 to provide a support for clothesline ropes which will hold the clothesline securely with an easy means of taking up the slack therein and a clothesline holder that will be quickly detachable from its position of support, convenient to manipulate as well as economical to manufacture 10 and sell at a reasonable price.

A particular purpose of my invention is to provide a rope holder and especially a clothesline holder which within the scope of my invention 15 may be made in several forms to accomplish the same or different purposes and especially made in a form which will permit a rope supported thereby to be suspended in almost any direction and in some forms of my invention any direction 20 from my supporting device as the center of support for that end of the rope.

In the meantime, I propose to provide in such an invention a rope supporting device for its several adaptations which in its respective forms are 25 attractive in appearance; are economical to manufacture and sell; are convenient to handle and practical to use.

I attain the objects of my invention by the device described in the annexed specification, recited in the claims and illustrated in the accompanying drawings in which like reference numerals indicate like parts in the several figures.

Referring to the drawings:

Fig. 1 is a perspective of one of the forms of 30 my invention wherein the semi-circular form of the supporting bracket makes it possible to support a rope or clothesline in any direction within a semi-circle from its point of support.

Fig. 2 is a perspective of that form of my invention wherein the supporting bracket is shaped 40 to define a rectangular channel while the rope holding channel plate detachably connected therewith is shaped to hold the rope supported thereby in only one direction and that is straight 45 out from the supporting bracket.

Fig. 3 is a perspective of one of those forms of 50 my invention wherein the supporting bracket holding the rope supporting channel plate is shaped to define an upright channel with a transverse slot through which a pair of hook members of the channel plate extend for the support of the rope.

Fig. 4 is a side elevation of a semi-circular bracket such as is shown in Fig. 1 with a slot 55 therein intermediate the top and bottom edges

thereof for the detachable support of a rope holding channel plate such as the one shown in Fig. 3.

Fig. 5 is a front view of that form of device of my invention shown in Fig. 4.

Fig. 6 is a perspective of that form of my invention wherein the rope supporting channel plate is held within the walls of the upright rectangular supporting bracket in which form the rope when held in place is supported within the walls of the supporting bracket and pressed 10 against the inner rear face thereof.

Fig. 7 is a perspective of that form of my invention wherein the curved supporting bracket is shaped to define a loop amounting to more than a half circle and from which a rope may be 15 supported in any direction within the scope of this loop.

Fig. 8 is a side elevation of that form of my invention as shown in Fig. 7 but which has an intermediate slot for the detachable support of 20 the rope holding channel plate which is shown in Fig. 3 and Fig. 4.

Fig. 9 is a perspective of that form of my device wherein the supporting bracket is shaped to define an upright cylindrical support adapted to 25 be secured to the top of a supporting post therefor and from which a rope may be held by a rope holding channel plate shown in the form indicated in Fig. 1 in any direction about the supporting bracket.

Fig. 10 is a perspective of the form of supporting bracket shown in Fig. 9 but supported on 30 a side wall.

Fig. 11 is a perspective similar to Fig. 9 with the one exception that in this figure the upright cylindrical bracket is provided with an intermediate slot between its top and bottom edges for the support of that type of rope holding channel plate illustrated in Figures 4 and 8.

Figure 12 is a figure similar to Figure 10 but 40 showing my upright cylindrical supporting bracket provided with a bracket adapted to support the same on a side wall.

Referring in detail to the design and construction of the several forms of my invention and 45 the advantages provided in each, I shall clearly and concisely set forth the merits of these forms, all of which fall within the scope of my invention.

For instance, attention is directed to that form 50 of my invention, disclosed in Fig. 1 wherein a channel plate 1 is provided with a pair of hook members 2 to hook over the edge of the semi-circular bracket 3 while at the bottom of this channel plate there is a pair of guard fingers 4 55

adapted to prevent undesired removal of plate 1 from bracket 3.

When a strain is exerted on rope 5 hanging over the top 6 of plate 1 with a weight on this 5 rope forcing the strain in the direction indicated by the arrow in Fig. 1 the tendency is for the bottom end 7 of plate 1 to squeeze this rope up against the outer surface of bracket 3 which results in holding the rope firmly and substantially; and in fact in this situation involving the first class leverage system the harder the strain 10 on rope 5 the harder will be the squeeze or pressure against that part of the rope in channel 1 between the lower end 7 thereof and bracket 3.

15 It will be noted that the semi-circular shape of bracket 3 will permit channel plate 1 to be hooked over bracket 3 any place on the semi-circle so that rope 5 may swing radially in any direction within the semi-circle; thus providing 20 a convenience that is always desirable especially in a clothesline adaptation of my invention. Bracket 3 is shown in Fig. 1 to be secured by bolts or screws 8 to a side wall 9.

In another modification of my invention I have 25 shown in Fig. 2 that form thereof in which channel plate 1 hooks over the front surface 10 of supporting bracket 11 with hook members 2 and guard fingers 4 serving the same purpose as is shown in Fig. 1.

30 In Fig. 4 I have shown a semi-circular bracket 12 corresponding in shape with bracket 3 and as a modification of bracket 3, I have provided in bracket 12 an intermediate slot 13 for the detachable support of a channel plate 14 having a 35 pair of upturned hook members 15 engaging the upper portion 16 of bracket 12 after they are inserted in the slot 13.

For this instance, rope 5 extending through 40 channel plate 14 with the strain or weight pulling outwardly on the top of plate 14 will cause an inward pressure of the bottom end 17 of plate 14 against this rope squeezing it against the outer surface of the lower portion 18 of bracket 12.

I show a front view of this modification of my 45 invention in Fig. 5 while in Fig. 3 I disclose in perspective that form of my invention wherein the upright rectangular bracket 19 is engaged through a front slot 20 by a channel plate 14 with hook members 15 of the channel plate holding the same in the same manner as is shown in Fig. 4.

I also show in Fig. 6 an upright channeled supporting bracket 21 having front support members 22 for the detachable engagement of the 55 rope supporting channel plate 23 in which arrangement a rope or a clothesline supported thereby will exert an outward strain against the top end 24 of plate 23 with a resulting inward pressure between the bottom end 25 of plate 23 60 and the bottom end of bracket 21 on the rope held thereby.

It will be noted that in Fig. 7 I provide a bracket 26 shaped to define a support that is greater than a half circle and as will be observed in this figure the rope holding channel plates 1 are attached in the manner shown in Fig. 1 with the additional advantage in this case providing a chance to mount these rope holding plates anywhere about bracket 26 so that the rope may extend therefrom in any direction within the limits of the curved portion of bracket 26. Thus this bracket may be supported upon the side of a post or wall by a screw or bolt secured thereto through holes 27 holding extension arms 28 for its support.

It will be also noted that in Fig. 8 there is provided a slotted modification of the bracket shown in Fig. 7 similar to the modification of that bracket illustrated in Fig. 1 where it is shown modified in Fig. 4 wherein the slot 13 with channel plate 14 holding the rope is disposed.

I have chosen in this application to further disclose two other modifications of my invention and in this connection attention is directed, first to Fig. 9 where bracket 29 is made in the form 10 of an upright cylindrical member adapted to be supported upon a post 30 so that the rope supporting channel bracket 1 may be detachably hooked upon bracket 29 as shown in this figure so that rope 5 may extend in any direction from 15 its point of support. In Fig. 10 I have illustrated a supporting bracket 31 similar to bracket 29 in all respects except its manner of support; and in this case I support this bracket on the side of a post or wall by a side bracket 32.

In Fig. 11 I am illustrating a modification of bracket 29 wherein a slot 33 is used for the detachable support of channel plate 14 engaging the same in the manner illustrated for the support of rope 5 while in Fig. 12 bracket 34 has a slot 25 35 operating in a similar manner. In this modification however of my invention bracket 34 is provided with a side bracket 36 adapted to support the same on the side of a post or wall.

Having thus described the nature of my invention what I claim is:

1. A rope hanger comprising in cooperative combination, a bracket shaped to define a support, and a channel plate hooked over the bracket for the support of a rope and also shaped to define a pair of spaced downwardly extending integral hanger hooks disposed intermediate the top and bottom of the channel plate, the sides of said plate deformed to define a central channel for the support of said rope; said sides also shaped to define a pair of bottom guard fingers respectively registering snugly under said hanger hooks and in spaced relation thereto respectively in the same plane therewith and respectively disposed at right angles to the position of the 40 hangers to provide stop means preventing unwarranted removal of said channel plate from said bracket by any vertical lift of the channel plate; said rope adapted to be supported within 45 said channel of the channel plate.

2. A rope hanger comprising in cooperative combination a metallic supporting bracket shaped to define an approximate half circular horizontal arc, adapted to be disposed in a horizontal position, a channel plate having a pair of integral 55 downwardly disposed hooks detachably supported over the periphery of said supporting bracket, said plate shaped to define a pair of parallel generally upright side plates forming a generally upright, curved channel and a rope operatively supported therein; and said side plates also respectively shaped to define each a pair of integral base guard fingers in the same plane with said downwardly disposed hooks, spaced therefrom and disposed at right angles to the position 60 of said hooks and registering beneath said supporting bracket and adapted to guard against unwarranted removal of the channel plate from said supporting bracket by a vertical lift of said plate.

3. A rope line hanger comprising in cooperative combination, a horizontally disposed curved supporting bracket, a detachable channel plate shaped to define a pair of integral, parallel, generally upright side plates with a rope supporting 70 75 80 85 90 95 100 105 110 115 120 125 130 135 140 145 150 155 160 165 170 175 180 185 190 195 200 205 210 215 220 225 230 235 240 245 250 255 260 265 270 275 280 channel between them and shaped to further define a pair of integral, intermediate, downwardly extending hanger hooks adapted to hang over the top periphery of said supporting bracket; and said side plates each respectively shaped at their bottom ends to define in the same plane with said hanger hooks, a pair of guard fingers in the same plane with said downwardly disposed hooks,

spaced therefrom and disposed at right angles to the position of said hooks and registering beneath said supporting bracket and adapted to guard against unwarranted removal of the channel plate from said supporting bracket by a vertical lift of said plate.
